(57) **CLAIM**

We claim the ornamental design for a wireless sound receiver, as shown and described.

DESCRIPTION

FIG. 1 is a perspective view of a wireless sound receiver showing our new design;

FIG. 2 is a front elevational view of the wireless sound receiver;

FIG. 3 is a rear elevational view of the wireless sound receiver;

FIG. 4 is a left side elevational view of the wireless sound receiver;

FIG. 5 is a right side elevational view of the wireless sound receiver;

FIG. 6 is a top plan view of the wireless sound receiver;

FIG. 7 is a bottom plan view of the wireless sound receiver; and,

FIG. 8 is a bottom rear perspective view of the wireless sound receiver.
